DESIGN FOR A REAL ESTATE SIGN

Charles A. Woolsey, Minneapolis, Minn.

Application September 14, 1934, Serial No. 53,284

Term of patent 7 years

To all whom it may concern:

Be it known that I, Charles A. Woolsey, a citizen of the United States, resident of Minneapolis, county of Hennepin, State of Minnesota, have invented a new, original, and ornamental Design for a Real Estate Sign, of which the following is a specification, reference being had to the accompanying drawing, forming part thereof, and in which

I claim:

The ornamental design for a real estate sign substantially as shown.

CHARLES A. WOOLSEY.
